FISH AND GAME CLEANING KNIFE

Michael W. Banowetz, Sr., Kenner, La., assignor
to The Master Troll Company, Kenner, La., a
corporation of Louisiana

Application October 28, 1952, Serial No. 22,024

Term of patent 14 years

(Cl. D22—3)

To all whom it may concern:

Be it known that I, Michael W. Banowetz, Sr., a citizen of the United States, residing at Kenner, county of Jefferson, State of Louisiana, have invented a new, original, and ornamental Design for a Fish and Game Cleaning Knife, of which the following is a specification, reference being had to the accompanying drawing, forming a part hereof.

Figure 1 is a view in side elevation of a fish and game cleaning knife, showing my new design.

Figure 2 is a view in side elevation, looking at the opposite side of the design to that shown in Fig. 1.

Figure 3 is a top plan view.

Figure 4 is a bottom plan view.

Figure 5 is a section taken on line 5—5, Fig. 1.

I claim:

The ornamental design for a fish and game cleaning knife, as shown.

MICHAEL W. BANOWETZ, SR.
